LOCKING MECHANISM

Ralph E. Smith, Galion, Ohio, assignor to The
Galion Metallic Vault Company, Galion, Ohio,
a corporation of Ohio

Application January 14, 1935, Serial No. 1,600

5 Claims. (Cl. 292—48)

This invention relates to locking mechanisms and, in particular, to devices for locking the hoods or covers of grave vaults to the bases thereof.

One object of this invention is to provide a locking device for locking the hood to the base of a grave vault at approximately the corners thereof, so as to provide an even tension and latching effect.

Another object is to provide a locking device of this character, wherein the latches are arranged in pairs at each end of the base, each pair being operated by a lever having a handle projecting outside the base.

Another object is to provide a grave vault with a base having a lock box incorporated therein and adapted not only to contain the locking mechanism, but also to add rigidity to the base and further decrease its tendency to sink into the earth.

Another object is to provide a locking system for locking grave vault hoods to the bases thereof, the latching members being connected to an operating lever which extends downward beneath the base and outward beyond it so that the locking mechanism may be operated by moving the portion of the lever beneath the base in the event that the end of the lever becomes broken off.

Another object is to provide a locking system for locking the hood of a grave vault to the base, wherein the hood is provided with an inwardly bent flange adapted to be engaged by the latching member of the lock and also to rest upon an upturned lip on the base in such a manner as to permit operation of the lock even though dirt may accidentally have fallen upon the base before the hood is placed over it.

In the drawings:

Figure 1 is a perspective view of a grave vault with its hood in position upon its base, and showing the lock-operating lever projecting from the base;

Figure 2 is a perspective view of the base of the grave vault of Figure 1, showing one of the latching members projecting from the side of the base, and the operating lever projecting from the end thereof;

Figure 3 is a top plan view of the grave vault base shown in Figure 2, with the top thereof broken away to show the details of the latching mechanism;

Figure 4 is the cross section through the end of the grave vault base shown in Figure 3, taken along the line 4—4 of Figure 3;

Figure 5 is an enlarged view, partly in cross section, showing the details of the latching mem-

ber of Figure 4 in its unlatching position;

Figure 6 is a view similar to Figure 5, but in a plane at right angles thereto;

Figure 7 is a view similar to Figure 3, but showing a modified construction;

Figure 8 is a cross section through the modified construction shown in Figure 7;

Figure 9 is a view similar to Figure 6, but showing the modified construction of Figures 7 and 8.

Referring to the drawings in detail, the grave vault embodying the locking device of my invention consists generally of a base 1 having a hood 2 which may be placed with its open side downward upon the base 1. The hood 2 is provided with handles 3 for the convenience of lowering the hood on to the base 1.

The base 1 comprises a base top plate, indicated by the numeral 4, this having downwardly extending flanges 5 at its outer edges. The flanges 5 are continued outward and upward to form a groove 6 with an upwardly projecting flange or lip 7. At each end of the base 1, a slot 8 is cut therethrough to accommodate the operating lever 9 of the locking mechanism, hereinafter described. The lip 7 is flared outward, as at 10 (Figure 2) in order to permit the passage and operation of the latch-operating lever 9.

The side flanges 5 of the base 1 are also provided with apertures 11 through which project the latching members 12 (Figure 2). One of these latching members 12 is arranged on each side of the base 1 near the corners thereof and interconnected to the other and to the operating lever 9 by mechanism described below.

The base top plate 4 is provided with suitable clips 13 which are adapted for the securing of the casket to the base. The hood 2 is provided at its lower edges with an inwardly extended flange 14 which is adapted to rest upon the lip 7 of the base 1. By this construction, the accidental falling of dirt into the grave before the hood has been lowered will merely fall into the trough 6 and not prevent the operation of the lock. The inwardly extended flange 14 of the hood 2 serves the further purpose of providing means for the engagement of the latching members 12 (Figure 4).

The latching mechanism (Figures 3 and 4) consists of the previously described latching members 12 extending through the apertures 11 in the side walls 5 of the base 1. Each latching member 12 is of double-walled construction, preferably formed from a single piece of material having wings 15 and 16 (Figure 6), which are bent toward one another and substantially at 55

right angles to the front face 17 of the latch member. A lower portion 18 of the front face 17 is bent backward to form the lower contact surface of the latch member 12 (Figures 4 and 5). The horizontal cross section through the latch member 12 thus roughly resembles a letter U.

Each latching member 12 is provided with holes 19 in the side wings 15 and 16 thereof, and through these is passed the pivot shaft 20 of the latch member. (Figures 5 and 6). In the construction shown, the pivot shaft 20 also passes through holes 21 in a pair of angle brackets 22, and the ends of the pivot shaft 20 are enlarged so as to secure the whole together. The bent portions 23 of the angle brackets 22 are secured, preferably by welding, to the base bottom plate 24. Each latching member 12 is thus mounted for free pivoting upon its pivot shaft 20, but is urged into a latching position by means of a looped coil spring 25 (Figures 4 and 5). This spring 25 is roughly U-shaped (Figure 3) and has a forward loop 26, the spring being coiled around the pivot shaft 20 and its arms 27 extended backward and upward into contact with the base plate 4 (Figure 4). The forward loop 26 engages the inner surface of the forward wall 17 of the latching member 12, urging it outward into a latching position. In this position the lower forward surface 18 of the latching member passes over the flange 14 of the grave vault hood 2, thus locking the hood securely to the base 1 and against the upwardly projecting lip 7 thereof.

The backwardly projecting wings 15 and 16 of each latching member 12 are so formed as to provide notched portions 30, which are arranged to serve as cam surfaces. These notches 30 are arranged to receive the lock slides 31. Each slide 31 consists of a U-shaped member attached to a control rod 32, as by the enlarged portions 33 thereon. Thus when the slide 31 is moved away from the side wall, the latch member will be disengaged from the hood (Figure 5); when the slide 31 is pushed inward toward the side wall 5, however, the upper portion of the slide will enter the notches 30 in the latch wings 15 and 16, allowing the latch member 12 to be rotated downward and outward through its aperture 11 and over the flange 14 of the hood 2.

The oppositely disposed latch members 12 (Figures 3 and 4) are operated simultaneously by their rods 32 through the action of the pivoted bar 34 into which the ends of the rods are inserted as in the holes 35. The bar 34 is secured to a cup-shaped spacer 36, such as by welding, in such a manner that the spacer 36 raises the bar 34 a sufficient distance above the bottom plate 24 of the base 1. The lock-operating rod 9 is likewise secured to the bar 35, as by welding, and is bent in the manner shown in Figure 6. The inner end 40 of the operating rod 9 is bent downward so that it passes through a hole 41 in the spacer 36 and likewise through a hole 42 in the bottom plate 24. A washer 43 and a cotter pin 44 prevent the displacement of the inner end 40 of the control rod 9.

Beyond the inner end 40, the control rod 9 is provided with the horizontally bent portion 45, which passes through a hole 46 in the spacer 36, and beyond this is bent downward in the vertical portion 47 which passes through a slot 48 in the bottom plate 24. Beyond this point the operating rod 9 extends outward in a horizontal portion 49 through the slot 8. By this construc-

tion, the operating rod 9 may be operated even though its outer end 50 may have been accidentally broken off. This is done by merely moving the horizontal portion 49 in a suitable direction either to lock or unlock the latching mechanism previously described.

The modified form of latching mechanism shown in Figures 7 to 9 inclusive is generally similar to that previously described, and similar parts are given corresponding numerals. Instead of the bar 34, however, a disk 51 (Figure 7) is employed to receive the ends of the control rods 32, and to this disk is attached the horizontal portion 52 of the lock-operating rod 53. On either side of the horizontal portion 52, the operating rod 53 is extended downward in vertical portions 54 and 55, the latter portion passing through a slot 56 in the bottom plate 24 (Figure 9), and thereafter is bent outward in a second horizontal portion 57. Thenceforth the portion 57 passes through a slot 58 near the lower edge of the base, and continues over a flange 10 in the outer lip 7 of the base.

The operation of the latching mechanism of my invention has been sufficiently disclosed in describing the construction thereof. To place the hood 2 upon the base 1, the former is merely lowered on to the latter. At the same time the lock-operating lever 9 is moved in such a manner as to draw the latch control rods 32 toward one another (Figure 3), thus withdrawing the latch members 12 into the interior of the base by way of the apertures 11. When the hood 2 is in its proper position upon the base 1, the lever 9 is moved in the reverse direction, allowing the latch members 12 to pass outward through their apertures 11 and engage the lower flange 14 on the hood 2.

The operation of the modified form of locking mechanism shown in Figures 7 to 9 is substantially similar to that of the form shown in Figures 3 to 6 inclusive. By the box-like construction of the base 1 to contain the locking mechanism, I have provided not only a container for the locking mechanism, but also a construction which adds to the rigidity of the base. This construction also further serves to prevent the vault from sinking into the earth.

When lever 50 is in locked position, it is not necessary to operate the lever because when setting the top on the base, the locks operate automatically. In Figures 3 or 4, the lever stays either in the locking or open position as shown in Figure 5. Part 34 extends through the box 24 and can be operated to unlock the bar from the top of the vault when the vault is standing on end, or if lever 50 should be broken off.

It will be understood that I desire to comprehend within my invention such modifications as may be necessary to adapt it to varying conditions and uses.

Having thus fully described my invention, what I claim as new and desire to secure by Letters Patent is:

1. In a locking system for a grave vault comprising a unitary hood adapted to be locked upon a base having a locking system enclosed in a portion thereof; a pair of horizontally pivoted latch members spring-pressed outwardly of said base and having downwardly disposed cam portions at the rear thereof, inverted U-shaped slide members disposed in said cam portions, operating rods each rigidly connected at one end to said slide members and pivotally connected at the other end to an operating member pivoted

about a vertical axis disposed between said latch members, whereby said operating member may be moved about its pivot and the latch members swung inwardly against spring pressure.

5. 2. In a locking system for a grave vault comprising a unitary hood adapted to be locked upon a base having a locking system enclosed in a portion thereof; a pair of horizontally pivoted latch members spring-pressed outwardly of said base and having downwardly disposed cam portions at the rear thereof, inverted U-shaped slide members disposed in said cam portions, operating rods each rigidly connected at one end to said slide members and pivotally connected at the 10 other end to an operating member pivoted about a vertical axis disposed between said latch members, and said rods being pivotally attached to said member upon directly opposite sides of said axis, said operating member comprising a centrally pivoted bar having an operating handle thereon extending beyond the base, whereby the latch members may be swung inwardly against spring pressure by swinging the operating member about its axis by means of the operating handle.

25. 3. In a locking system for a grave vault comprising a unitary hood adapted to be locked upon a base having a locking system enclosed in a portion thereof; a pair of horizontally pivoted latch members spring-pressed outwardly of said base and having downwardly disposed cam portions at the rear thereof, inverted U-shaped slide members disposed in said cam portions, operating rods each rigidly connected at one end to said 30 slide members and pivotally connected at the other end to an operating member pivoted about a vertical axis disposed between said latch members, said operating member comprising a centrally pivoted plate having an operating handle thereon, whereby said operating member may be moved about its pivot and the latch members swung inwardly against spring pressure.

4. In a locking system for a grave vault, a pair of oppositely disposed outwardly spring urged latch members pivotally mounted about horizontal axes and having backward extending arms with cam surfaces on the underside thereof, a pair of slide members of inverted U form each disposed with its top in contact with the cam surfaces of one of said latch members and guided for sliding movement in a direction perpendicular to the axis of said latch member, a pair of control rods each having one end rigidly attached to one of said slide members, and an operating member pivotally mounted on a vertical axis disposed between said latch members, each of said rods having its other end pivotally attached 10 to said operating member at opposite sides of the axis thereof and being so bent that rotary movement of said operating member will cause sliding movement of said slide members inwardly, whereby to draw the latch members inwardly 15 against spring pressure.

5. In a locking system for a grave vault, a pair of oppositely disposed outwardly spring urged latch members pivotally mounted about horizontal axes and having backward extending arms 25 with cam surfaces on the underside thereof, a pair of slide members of inverted U form each disposed with its top in contact with the cam surfaces of one of said latch members and guided for sliding movement in a direction perpendicular 30 to the axis of said latch member, a pair of control rods each having one end rigidly attached to one of said slide members, and a disk pivotally mounted on a vertical axis disposed between said latch members, each of said rods having its other 35 end pivotally attached to said disk at opposite sides of the axis thereof and being so bent that rotary movement of said disk will cause sliding movement of said slide members inwardly, whereby to draw the latch members inwardly against 40 spring pressure.

RALPH E. SMITH.
